UNITED STATES PATENT OFFICE.

HENRY M. SUTTON, WALTER L. STEELE, AND EDWIN G. STEELE, OF DALLAS, TEXAS.

PROCESS AND APPARATUS FOR SIZING OR CLASSIFYING COMMINUTED MATERIALS.

1,114,935.

Specification of Letters Patent.

Patented Oct. 27, 1914.

Application filed January 22, 1914. Serial No. 813,716.

To all whom it may concern:

Be it known that we, HENRY M. SUTTON, WALTER L. STEELE, and EDWIN G. STEELE, citizens of the United States, residing at Dallas, in the county of Dallas and State of Texas, have invented certain new and useful Improvements in Processes of and Apparatus for Sizing or Classifying Comminuted Materials, of which the following is a specification, reference being had therein to the accompanying drawing.

This invention relates to a process of and an apparatus for sizing or classifying comminuted material, and is in the nature of an improvement upon our pending application Serial Number 780,360, filed July 21, 1913; the object being to provide novel means for vibrating the endless belt or deck in order to impart to the particles thereon, an accelerated movement in the direction of their natural travel by gravity.

Another object of the invention is to provide an agitating means for the endless belt or deck in the form of an angular bar having tapering faces increasing in width from the upper end toward the lower end, whereby the vibration of the belt or deck will be increased from the upper edge to the lower edge in order to impart the accelerated movement to the particles thereon.

Another and further object of the invention is to provide means for imparting a constant accelerated movement to the particles in the direction of their natural travel by gravity or at right angles or approximately so, to that of their travel with the belt, in order to allow the particles in one particular zone to clear the way for the particles just above whereby each particle in every zone, is allowed more freedom of movement in order to increase the effectiveness of the sizing apparatus.

Another and further object of the invention is to provide a continuously moving supporting surface with agitating means which imparts to the surface, an undulatory movement in zones extending transversely across the supporting surface in order to allow the particles in each zone to more clearly differentiate themselves from those of the adjacent zone, each zone being vibrated in such a manner that the particles will travel contiguously across the supporting surface with free movement, thereby allowing the apparatus to carry out the process of separating comminuted material at a greater speed than the apparatus previously constructed.

Another object of the invention is to provide a roughened sizing surface whose resistance in the direction of the flow of the material by gravity increases progressively and in the same direction as does the increase in the vibrations in order to constantly check the tendency of the particles toward racing or bouncing along the surface which would be fatal to good sizing; the vibration increasing in intensity in proper proportion to the increasing resistance in order to give the flowing pulp a proper accelerated movement.

We are aware that apparatuses have been constructed for separating seed and the like, in which a transversely inclined continuously moving belt or support has been provided with agitating means for separating the round seed from the flat seed, but in this class of separator, the material is not separated according to volume of the particles without regard to shape or difference in specific gravity, or in other words, particles that are square or flat have the same volumetric dimensions as round or oval ones, or any other shape, as is the case with our process of separating comminuted material.

This can be thoroughly explained by comparing the action of rolling particles down the inclined surface where the particles are free to move independently of the action of any of the other particles, other than the surface over which they are rolling such as takes place with seed separators now in use having inclined continuously moving surfaces. In this class of machine, if a round and flat particle are started down an inclined surface, the round particle will out-distance the flat one in speed and arrive at the bottom of the inclined surface ahead of the flat one. With our apparatus and process of separating comminuted material in which the particles are separated according to volume, if a mixture of comminuted material having different volumetric dimensions, is placed on a continuously moving roughened inclined surface which is being vibrated, these particles have a restricted field of action influenced by the surface over which they are traveling and their relative amount of friction with each other and a

sizing action takes place according to the volume of each particle, and while it is essential in this process, to give the particles an accelerated movement while they travel 5 across a continuously moving surface, it must be clearly understood that these particles are restricted in relation to the slope of such surface and their restrictions with each other, so that they do not race or bounce 10 along said surface, but by the general vibration of the surface, move gently down the sizing surface in zones. This is an important differential feature over any form of seed separator in the prior art which has for 15 its object, the separation of various cereals or seeds strictly in regard to shape and not to volume, because in this class of seed separator, each seed must be allowed such extreme freedom that it does not come into 20 contact with any other seed or in other words, the spherical seeds do not come into contact with the seeds of irregular shape. Otherwise, their motion would be arrested 25 and the process defeated, as they allow the round cereals to race or bounce on the surface to avoid the flat or irregular-shaped seeds while with our process, the particles of 30 comminuted material are subjected to a resistance partly influenced by the surface and partly by the close association of the particles 35 with one another, and while with our process, we call for an accelerated movement of the particles in order to carry out our process upon our sizing apparatus, these particles 40 always move in restricted paths; each particle being bounded on all sides by its fellow particles so as to allow only a restricted field of movement in order that each zone is 45 imparted with a constantly accelerated movement, the particles of which move in unison contiguous to one another and do not race or bounce upon the separating surface.

From the above statement, it will be seen that our process of and apparatus for sizing comminuted material is differentiated 50 from apparatuses and process as hereinbefore employed by subjecting the particles upon a continuously moving roughened surface, to an undulatory movement, in order to impart an agitation to the material from 55 under the surface which increases in intensity at an angle to the travel of the particles with the surface, whereby the particles are subjected to an accelerated movement in the direction of their travel by gravity, and to a progressively increasing 60 resistance in the direction of the travel of the particles by gravity in order to constantly check the tendency of the particles 65 toward racing or bouncing along the surface, which enables the apparatus to carry out the process of sizing and separating comminuted material with better results.

Other and further objects and advantages 65 of the invention will be hereinafter set forth

and the novel features thereof defined by the appended claims.

In the drawings Figure 1, is a perspective of an apparatus for carrying out our improved process for sizing comminuted material; Fig. 2, is an elevation of the endless supporting surface or deck, showing the agitating rollers; Fig. 3, is a transverse enlarged section through the supporting surface or deck, showing the agitating roller 70 and in dotted lines, the movement imparted to said surface or deck by the rotation of said roller, which increases in intensity from the upper edge toward the lower edge in order to impart the accelerated movement 75 to the particles thereon; Fig. 4, is a side elevation of the roller, detached; Fig. 5, is an end elevation; Fig. 6, is a transverse section through the corrugated belt having longitudinally arranged V-shaped grooves 80 formed therein which gradually increase in depth toward its lower edge; Fig. 7, is a transverse section through a slightly modified 85 form of the belt; the corrugations and grooves of which are formed upon curved 90 lines which increase in depth toward the lower edge thereof; the rounded grooves formed thereby offering less resistance to the material in its movement over the same than the straight-sided grooves, as shown in 95 Fig. 6; Fig. 8, is a detail transverse section of a slightly modified form of apparatus for carrying out the process of sizing comminuted material in which the deck 100 frame is pivotally mounted at its upper edge and supported upon a rod carried by an eccentric at its lower edge forming means 105 for agitating the deck or supporting surface vertically in order to cause the deck to rise and fall as the eccentric is revolved in such a manner that the particles upon the deck will be subjected to an accelerated movement at an angle to the direction of travel of the surface, whereby the particles upon the surface will be subjected to an 110 agitation which increases in intensity from the upper edge to the lower edge. Fig. 9, is a transverse section through an apparatus showing one means of supporting the deck 115 frame in order to change the inclination thereof; Fig. 10, is a perspective of a belt having longitudinally arranged grooves formed therein; and Fig. 11, is a perspective of a belt having diagonally arranged corrugations.

Like numerals of reference refer to like parts in the several figures of the drawings.

In the preferred form of apparatus as shown, 1 indicates a deck frame which is 125 preferably adjustably supported as shown in Fig. 9 by depending curved slotted arms 1^a through which extend threaded studs 1^b carried by the frame 1^c supported on the base 1^d; the studs being provided with hand 130

wheels 1^e for clamping said arms in their adjusted position, the opposite side of the deck frame being connected to the frame 1^e by hinges or suitable pivots 1^f, in order that the inclination of the deck frame can be readily adjusted so as to allow the process of classifying comminuted material to be carried out successfully and while the degree of inclination may be varied, we do not wish to limit ourselves to any particular construction of supporting or mounting this deck frame, as various forms can be used without departing from the spirit of our invention.

15. The deck frame 1 is provided with suitable bearings at each end in which are mounted shafts 2 and 3 carrying rollers 4 and 5 over which is arranged, an endless belt 6, preferably formed of rubber or some 20. suitable flexible material having diagonally or longitudinally arranged corrugations preferably increasing in size from the upper edge toward the lower edge in order to provide a roughened sizing surface which has a 25. progressively increasing resistance to the particles of comminuted material delivered thereon in the direction of the flow of the material by gravity.

In the form of corrugated belt as shown 30. in Fig. 6, the grooves formed therein are substantially V-shape in cross section and it will be noted that they gradually increase in depth from the upper edge of the belt toward the lower edge which exerts a greater 35. resistance to the material thereon in its movement by gravity. The shaft 3 is provided with an extension carrying a pulley 7 over which passes a belt 8^x which is driven by a change-speed mechanism 9^x in order 40. that the speed of travel of the belt can be regulated, the form of change-speed mechanism being the well-known form of change-speed mechanism now in use.

45. Mounted intermediate the shafts 4 and 5 in the deck frame 1, are a series of shafts 8 carrying angular tapering rollers 9 preferably hexagon in cross section, having faces which increase in width from the upper portion to the lower portion, these faces being normally held in contact with the under surface of the deck or belt 6 so that when they are rotated, the belt will be subjected to an undulatory movement in order 50. that the same may be agitated in such a manner that the intensity of agitation will be increased from the upper edge toward the lower edge, whereby the particles will be subjected to an accelerated movement at an angle to the movement of the continuously moving belt or supporting surface. The shafts 8 extend outwardly beyond the upper side bar of the frame 1 and are provided with beveled gears 10 which mesh with beveled gears 11 carried by a 55. longitudinally arranged shaft 12, which is

preferably supported by the deck frame in order that the frame may be moved so as to hold the coöperating gears in mesh as the inclination of the supporting surface is adjusted and while the supporting means for 70 the shaft herein shown, is not disclosed, it is of course understood that suitable bearings can be extended from the frame for this purpose. It will be seen that by connecting each shaft carrying the roller to a 75 driving means rotating upon a shaft, all of the angular rollers will be rotated in unison in order to impart to the traveling inclined supporting surface, an agitation arranged in zones extending transversely across the 80 supporting surface; which agitation increases in intensity from the upper edge to the lower edge which is one of the fundamental principles upon which our improved process of sizing comminuted material is 85 carried out, in order to increase the capacity of a sizing apparatus in sizing comminuted material in which the particles differ according to volume and not purely to shape.

One end of the shaft 12 carries a pulley 90 13 over which passes a belt 14 carried by a change-speed mechanism 15 constructed substantially the same as the change-speed mechanism 9^x whereby the speed of the shaft 12 can be adjusted in order to increase 95 or decrease the speed of travel of the agitating rollers to suit the class of comminuted material being sized upon the apparatus, as with certain classes of comminuted material a greater speed of vibration is desired 100 than with other classes and by having separate driving mechanism for the continuously moving belt and the agitating means, these can be adjusted independently.

A gate-controlled hopper 16 is carried by 105 a suitable support and is so arranged that comminuted material is delivered upon the upper edge of the belt or deck at the receiving end and material delivered therefrom is at once subjected to the sizing action 110 of the belt, the belt carrying the pulverulent material which is too fine to move by gravity along with the run of the belt, the larger particles which differentiate according to volume, at once starting to move in 115 zones transversely of the belt.

Arranged along the lower edge of the belt frame and extending slightly under the edge of the belt, is an inclined apron 17 adapted to receive the particles sized or 120 classified by the endless belt and said apron is provided with a longitudinally centrally arranged bar 18 spaced therefrom and under which are arranged deflecting or spacing fingers 19 which are preferably held in 125 adjusted position by frictional contact exerted thereon by springs 19' carried by said fingers and while we have shown this particular construction of finger, it is of course understood that we do not wish to limit 130

ourselves to any particular construction of apron or finger, as various other forms of aprons for this purpose can be used without departing from the spirit of our invention.

5 A similar apron 21 is arranged at the end of the belt having a spacing bar 22 and separating or deflecting fingers 23. In our companion application, a separation of the particles takes place entirely before the end 10 of the belt has been reached, only the pulverulent material reaching the end of the belt and with this construction of sizing apparatus it has been found by increasing the speed of the belt to increase the capacity of 15 the apparatus, a sizing action occurs at the end of the belt, making it necessary to place the apron and deflecting fingers in this position.

In the form of belt shown in Fig. 7, we 20 provide a roughened surface X having diagonally or longitudinally arranged corrugations, the grooves and ribs formed thereby being formed upon curved lines in order to decrease the resistance; the grooves 25 formed thereby gradually increasing in depth from the upper edge toward the lower edge thereof.

In the apparatus shown in Fig. 8, we employ a deck frame 24 pivotally mounted as 30 shown at 25 at an inclination, having a bearing 26 at its lower end on which is mounted a pitman rod 27, carried by an eccentric 28 mounted upon a shaft 29 provided with a pulley 30 over which the drive belt 35 31 passes. The frame carries a roller 31 at each end, over which the endless belt or deck 32 passes and this deck or belt is likewise provided with diagonally or longitudinally arranged corrugations to form a resistance and by the movement of the eccentric, the belt is given a greater perpendicular movement at its lower edge than at its upper edge, whereby a constantly accelerated speed is imparted to the particles 45 traveling across the same in the line of their natural movement by gravity and while we have shown an eccentric, it is of course understood that a crank could be employed or any other suitable driving means, for giving the deck frame a greater movement at its lower edge than at its upper edge.

In the operation of the apparatus for carrying out the process for sizing comminuted material, the belt or deck is driven continuously at the desired rate of speed and the agitating rollers are likewise driven at the desired rate of speed, the speed of the belt and rollers being first determined by the nature of the material to be sized and when 55 the gate of the hopper is opened, comminuted material will be delivered upon the endless roughened sizing surface at a point X and referring to Fig. 1, the shaped lines indicate the travel of the particles in the 60 zones according to the volumetric dimen-

sions thereof; the letters A to H inclusive, indicating the different zones of the respective particles and it will be noted that the particles in the zone A are enabled to move with such freedom as to more clearly differentiate themselves from the particles of the zone B and so on throughout the different zones at a diminished rate of vibration toward each zone. In this manner, each class of particles partakes of more freedom of 70 motion than would be possible if the belt was simply vibrated by angular rollers having the same dimension throughout their length.

In order to clearly set forth the fundamental 80 principle for carrying out or improved process of sizing comminuted material, by giving the continuously moving sizing surface a continuously increasing vibration commencing at the upper edge of said surface 85 and extending transversely across the same in the direction of the natural movement of the particles by gravity and at the same time subjecting said particles in their movement by gravity, to a progressively increasing resistance, a greater efficiency in the sizing of 90 the particles is obtained as well as a greater capacity. This is accomplished by giving the particles an accelerated movement in the line of their natural travel by gravity or 95 transversely of the continuously moving surface, which enables each class of particles in a given zone to free itself from the zone of particles immediately above, thus permitting an increased feed to the 100 continuously moving surface and thereby increasing the amount of each product obtained. Through the medium of the agitating rollers, a graduated vibration is obtained which permits the particles to move 105 with greater freedom and thus a more effective sizing of the various products, is obtained.

It has been found by experimenting with an apparatus of this character, that a perfect sizing can be obtained with various characters of material and while the apparatus is particularly constructed for sizing comminuted ore, it will work equally well upon any comminuted material as the fundamental principle of this invention, is to provide a roughened continuously moving transversely inclined supporting surface for the material which when on said surface, is subjected to an accelerated movement in 110 the direction of travel by gravity causing the particles thereon, to move contiguous to one another in their movement at an angle to the movement of the roughened continuously moving supporting surface.

115 From the foregoing description, it will be seen that we have provided an apparatus for sizing comminuted material in which a continuously moving endless belt is employed having corrugations arranged at an 120 125 130

angle to the movement of the belt; said belt being arranged upon an incline in order to subject the particles delivered thereon, to the force of gravity, means being provided for agitating the belt to increase the speed of travel by gravity, said corrugations forming a resistance to the material against the force of gravity to cause the particles in their movement by gravity, to travel contiguously with one another.

In the description, we have described an apparatus of such a construction that a belt can be employed thereon with diagonally or longitudinally arranged corrugations and it has been found in practice that when operating on certain classes of material, that a belt having diagonally arranged corrugations obtains better results than a belt having longitudinally arranged corrugations; the fundamental principle of this invention being to exert a resistance to the particles in their movement by gravity to cause the particles to travel contiguously with one another so as to overcome the tendency of the particles to race or bounce in their movement over the surface, and we do not wish to limit ourselves to any particular construction of apparatus, as various forms of apparatus can be employed without departing from the spirit of our invention.

We claim:

1. The process of sizing a mass of pulverulent material, consisting in feeding the material dry upon a continuously moving transversely inclined roughened supporting surface, imparting to said mass an accelerated movement in the direction of its travel by gravity, causing the components of said mass to deviate from the line of normal movement contiguously at angles proportionate to their sizes, and separately collecting the sized particles.

2. The process of sizing a mass of comminuted material, consisting in feeding the material dry upon a continuously moving transversely inclined roughened supporting surface, imparting to said material an accelerated movement at an angle to the continuous movement thereto, causing the components of the mass to deviate from the line of normal movement at angles proportionate to their sizes, and separately collecting the thus sized particles.

3. The process of sizing material, which consists in feeding unsized comminuted material to a continuously moving conveying surface, subjecting said material to the force of gravity at an angle to the continuous movement of said surface, subjecting said material to a series of vibrations from below, said vibrations increasing in intensity from the point of feed transversely across the conveying surface, to cause an accelerated movement of the particles thereon in lines deviating according to sizes of the par-

ticles from the line of normal movement, and separately collecting the thus sized particles.

4. The process of sizing consisting in supporting and continuously moving unsized comminuted material upon a surface having a progressively increasing resistance, subjecting said material to the force of gravity and to an undulatory vibration to cause the particles to travel in lines deviating according to sizes of the particles from the lines of normal movement, and separately collecting the thus sized particles.

5. The process of sizing material, consisting in feeding unsized comminuted material upon a continuously moving roughened surface, subjecting said material to the force of gravity and to an undulatory movement to cause the particles to travel according to their volumetric dimensions at different rates of speed in lines deviating from the line of normal movement of said material, and separately collecting the thus sized particles.

6. The process of sizing a mass of comminuted material according to its volumetric dimensions, consisting in continuously moving unsized comminuted material, subjecting said material to the force of gravity at an angle to the movement of said material, exerting a deflecting resistance to said material in its travel by gravity and imparting to said material an accelerated movement in the direction of travel by gravity, and separately collecting the thus sized particles.

7. A sizing apparatus, comprising an inclined endless deck having diagonally arranged corrugations forming a deflecting resistance against the force of gravity, change-speed mechanism for driving said deck, means for imparting undulatory vibrations to said surface, and means for separately collecting the sized particles delivered from said surface.

8. A sizing apparatus, comprising a continuously moving inclined deck having longitudinally arranged deflecting resistance members, angular rollers arranged under said deck for vibrating the same, means for driving said rollers in unison, and change-speed mechanism for driving said deck.

9. In an apparatus for classifying comminuted material, the combination with a continuously moving deck, of spaced angular rollers arranged under said deck having graduated faces, and means for driving said rollers in unison.

10. In an apparatus for classifying comminuted material, the combination with a continuously moving inclined deck, of tapering angular rollers arranged under said deck, and means for driving said rollers in unison.

11. In an apparatus for classifying comminuted material, the combination with a continuously traveling conveyer surface, means for feeding material thereon, means for agi-

tating said surface, with agitations increasing in intensity at an angle to the travel of said surface and in the direction of travel of the material by gravity.

5 12. A sizing apparatus, comprising a frame, an endless belt mounted in said frame, tapering angular rollers arranged under said belt, and means for driving said tapering angular rollers in unison so as to 10 impart to said belt vibrations increasing in intensity transversely thereof.

13. A sizing apparatus, comprising a deck frame, rollers mounted in said frame, a flexible belt having a roughened surface mounted upon said rollers, shafts mounted in said frame, tapering angular rollers mounted upon said shaft contacting with the under surface of said belt, gears carried by said shaft, a driven shaft carrying gears meshing 20 with said gears, and a change-speed mechanism for driving said driven shaft.

14. A sizing apparatus, comprising a deck frame, a flexible deck mounted therein, and a series of spaced tapering angular rollers 25 arranged to contact with the under face of said deck.

15. A sizing apparatus, comprising a deck frame, a continuously moving deck mounted in said frame, tapering rollers having faces 30 increasing in width from one end to the other arranged under said deck, and means for driving said rollers in unison.

16. A sizing apparatus, comprising a deck frame, a continuously moving deck mounted 35 in said frame, means for supporting said deck at an inclination transversely, a series of tapering angular rollers arranged under said deck frame having faces increasing in width from the upper edge of said deck to 40 the lower edge of said deck.

17. The process of sizing material, consisting in continuously moving unsized comminuted material in one direction, subjecting said material to the force of gravity and 45 to a progressively increasing resistance in the direction of the flow of the material by gravity, and imparting to said material an accelerated movement in the direction of travel by gravity, to cause said particles to 50 travel in lines deviating according to size of the particles from the normal movement of said material.

18. The process of sizing comminuted material, consisting in feeding a mixture of 55 said material to a transversely inclined continuously moving support, imparting to said particles an accelerated movement in the direction of their natural travel by gravity, subjecting said material in its movement by gravity to a progressively increasing resistance, and separately collecting the graded 60 particles.

19. The process of sizing comminuted material, consisting in feeding a mixture of 65 said material to a transversely inclined con-

tinuously moving progressively increasing roughened surface, imparting to said particles in transversely extending zones, an accelerated movement in the direction of their natural travel by gravity, and separately 70 collecting the thus separated particles.

20. The process of sizing a mass of comminuted material, consisting in continuously moving said material upon a roughened supporting surface having a progressively increasing resistance, subjecting said material to the force of gravity and to an accelerated movement in the direction of travel by gravity, to cause the different components to 80 travel according to their volumetric dimensions at different rates of speed in lines deviating from the lines of continuous movement of said material, and separately collecting the thus sized particles.

21. The process of sizing a mass of comminuted material, consisting in feeding said material upon a continuously moving inclined irregularly roughened supporting surface, subjecting said material to an accelerated movement in the direction of travel 90 by gravity, and separately collecting the thus sized particles.

22. The process of sizing a mass of comminuted material, consisting in supporting and continuously moving said material upon an inclined roughened surface having a diagonally progressively increasing deflecting resistance, subjecting said material to the force of gravity and to an undulatory vibration to cause the particles to travel in lines 95 deviating from the lines of normal movement, and separately collecting the thus sized particles.

23. The process of sizing a mass of unsized particles, consisting in subjecting said particles when moving in a continuous direction to a progressively increasing resistance and to the action of vibrations varied in their intensity in lines transversely of the continuous movement of said material, and 105 separately collecting the thus sized particles.

24. The process of sizing comminuted material, consisting in continuously moving the material in one direction, subjecting said material to the action of gravity in a direction transverse to the continuous movement, subjecting said material to a progressively increasing resistance in its movement by gravity, imparting to said material, an accelerated movement in the direction of travel 110 by gravity, and separately collecting the thus sized particles.

25. A sizing apparatus, comprising an inclined endless deck having diagonally arranged corrugations forming a progressively 125 increasing deflecting resistance against the force of gravity, means for driving said deck, means for vibrating said deck, and means for separately collecting the sized particles delivered from said surface.

26. A sizing apparatus, comprising a continuously moving transversely inclined deck provided with corrugations increasing in size from the upper edge toward the lower edge thereof, mechanism for driving said deck continuously, mechanism for imparting to said deck a series of spaced undulatory vibrations, and driving means for said vibrating means.
27. In an apparatus for classifying comminuted material, the combination with a continuously moving transversely inclined deck having a sizing surface provided with corrugations gradually increasing in size from the upper edge toward the lower edge thereof, of spaced angular rollers arranged under said deck having graduated faces, and means for driving said rollers in unison.
28. In an apparatus for classifying comminuted material, the combination with a continuously moving transversely inclined deck, having an irregular corrugated surface, of tapering angular rollers arranged under said deck, and means for driving said rollers in unison.
29. The process of sizing a mass of comminuted material, consisting in supporting said material upon a continuously moving roughened transversely inclined support having a progressively increasing resisting surface, subjecting said material to graduated vibrations increasing in intensity in lines extending transversely of said surface, and means for separately collecting the thus sized particles.
30. The process of sizing a mass of comminuted material, consisting in continuously moving said material upon a transversely inclined supporting surface having a progressively increasing resistance to the material in the direction of flow by gravity, imparting to said material an accelerated movement in lines extending transversely of said surface, and means for separately collecting the thus sized particles.
31. A sizing apparatus having a continuously moving inclined deck, said deck having a surface provided with longitudinally arranged gradually increasing corrugations, and means for vibrating said surface in lines extending transversely of said surface.
32. The process of sizing comminuted material, consisting in supporting said material upon a continuously moving transversely inclined surface having longitudinally arranged corrugations forming a progressively increasing resistance to the material in its travel by gravity upon said surface, and subjecting said material in its movement upon said surface to a series of graduated vibrations extending transversely of said surface.
33. The process of sizing comminuted material, consisting in feeding a mixture of said material to a transversely inclined con-
- tinuously moving supporting surface, imparting to said particles in transversely extending zones, an accelerated movement in the direction of their natural travel by gravity, subjecting said particles to a progressively increasing deflecting resistance in their movement by gravity, and separately collecting the thus sized particles.
34. The process of sizing comminuted material, consisting in feeding a mixture of said material to a transversely inclined continuously moving support, vibrating said support to increase the speed of travel of said particles thereon in the direction of their natural travel by gravity, subjecting said material in its movement by gravity to a progressively increasing resistance, and separately collecting the graduated particles.
35. The sizing of a mass of comminuted material, consisting in moving said material in one direction, subjecting said material to the force of gravity and to vibrations, subjecting said material to a progressively increasing resistance in its movement by gravity, and separately collecting the thus separated particles.
36. The process of sizing comminuted material, consisting in continuously moving said material in one direction, subjecting said material to the force of gravity at an angle to the movement of said material, and presenting to said material in the direction of travel by gravity, a progressively increasing resistance, and separately collecting the thus sized particles.
37. The process of sizing a mass of unsized particles, consisting in continuously moving said particles in one direction, agitating said particles to the action of gravity at an angle to the continuous movement of the particles, exerting a gradually increased resistance on said particles in their movement by gravity to cause the particles to move contiguous to one another in zones deviating from the continuous movement of the particles, and separately collecting the thus separated particles.
38. A sizing apparatus, having a continuously moving flexible endless belt provided with corrugations arranged at an angle to the movement of the belt, said corrugations gradually increasing in depth transversely thereof.
39. The process of sizing a mass of material, consisting in continuously moving said material in one direction, agitating said material, subjecting said material to the force of gravity at an angle to the continuous movement of the material, to cause the different components of the mass to travel contiguously according to the sizes of the particle thereof, at different rates of speed in lines deviating from the line of continuous movement of said material, and separately collecting the thus sized particles.

40. The process of sizing a mass of comminuted material, consisting in continuously moving the mass of material away from the point of feed in one direction, subjecting the mass to the force of gravity, exerting a resistance to the mass of particles in its movement by gravity, to cause the unpulverized particles to travel contiguously in lines deviating from the line of movement of the pulverized material, at angles proportionate to their sizes, and separately collecting the so sized particles.

41. The process of sizing a mass of particles of different sizes, consisting in feeding said particles on to a roughened surface moving continuously in one direction, subjecting said material in its continuous movement to the force of gravity at an angle to the continuous movement of said material, agitating said material upon said surface to aid the force of gravity to overcome the resistance of the roughened surface upon which said material is traveling, to cause particles of said material to travel contiguously in lines deviating from the line of continuous movement at angles proportionate to their relative sizes, and separately collecting the thus sized particles.

42. The process of sizing a mass of material having particles of different sizes, consisting in feeding and continuously moving said material away from the point of feed in one direction, permitting the components of said material to respond to gravity sufficiently to cause the granular particles thereof, to travel contiguously according to the size of the particles thereof, at different rates of speed in lines at angles to the continuous movement of said material proportioned to the sizes of said components, agitating said material continuously, and separately collecting the thus sized particles.

43. The process of sizing material, consisting in feeding said material dry, upon a continuously moving inclined roughened

surface, agitating said surface to cause the particles thereof to move contiguously upon said surface in lines deviating in proportion to the sizes of said particles from the line of travel of the continuously moving surface, and separately collecting the thus sized particles.

44. The process of sizing comminuted material, consisting in feeding and continuously moving said material in dry condition away from the point of feed upon a continuously moving transversely inclined roughened supporting surface, exerting a resistance to said material in its movement by gravity upon said supporting surface to cause the particles thereof to travel contiguously, agitating said material upon said supporting surface, to aid the force of gravity to cause the particles thereof to travel in lines deviating proportionate to their sizes from the line of continuous movement of the material, and separately collecting the thus sized particles.

45. The process of sizing a mass of material, consisting in feeding and continuously moving said material when dry, away from the point of feed, continuously agitating said mass of material without propelling the material, subjecting said material to the force of gravity to cause the granular particles thereof according to their different sizes, to deviate in lines from the normal movement of the material, exerting a resistance to said material in its movement by gravity to cause the particles thereof to travel contiguously, and separately collecting the thus sized particles.

In testimony whereof we affix our signatures in presence of two witnesses.

HENRY M. SUTTON.
WALTER L. STEELE.
EDWIN G. STEELE.
